(57) CLAIM

The ornamental design for a handle substantially as shown and described.

DESCRIPTION

FIG. 1 is a front, top perspective view of a handle in accordance with my design;

FIG. 2 is a top view of the handle;

FIG. 3 is a bottom view of the handle;

FIG. 4 is a front view of the handle;

FIG. 5 is a back view of the handle;

FIG. 6 is a left view of the handle;

FIG. 7 is a right view of the handle; and,

FIG. 8 is a partial enlarged view of the handle based on the broken circle "8" shown in FIG. 1.

The dashed lines in the figures illustrate the portions of the design that form no part of the claimed design. None of the broken lines form any part of the claimed design.
